Attorney

UNITED STATES PATENT OFFICE.

CARL V. VOELKER, OF WILKES-BARRE, PENNSYLVANIA.

DRY CLOSET.

1,270,075.

Specification of Letters Patent. Patented June 18, 1918.

Application filed February 17, 1916. Serial No. 78,866.

To all whom it may concern:

Be it known that I, CARL V. VOELKER, a citizen of the United States, residing at Wilkes-Barre, in the county of Luzerne and 5 State of Pennsylvania, have invented certain new and useful Improvements in Dry Closets, of which the following is a specification.

The present invention relates to the class 10 of baths and closets and more particularly to new and useful improvements in dry closets.

An object of the present invention is to provide a sanitary closet of the class described 15 in which the receptacle thereof is readily removable for emptying and cleansing.

Another object of this invention is to provide a sealing entrance means for the receptacle to prevent the escape of impure air and bad odors, manipulating means being provided therefor.

A further object of this invention is to provide an improved removable lid for the 20 receptacle to permit of access to the interior of the receptacle for repairing or cleaning.

Other objects and advantages will appear from the following detail description and the claim, taken with an inspection of the 30 accompanying drawing, in which—

Figure 1 is a longitudinal vertical sectional view of a dry closet embodying the improvements of my invention.

Fig. 2 is a transverse vertical sectional view taken on the line 2—2 of Fig. 1, looking in the direction of arrows.

Referring more specifically to the drawing, wherein similar characters of reference designate like and corresponding parts 40 throughout the various views, 1 designates the floor, 2 and 3 the side and rear walls, respectively, on the outhouse, a roof 4 being arranged on said walls. A seat 5, having the usual opening 6, is mounted on the walls 2 and 3 secured on the ledges 7.

The device of my invention includes a receptacle designated in its entirety as 8 and having side and end walls 9 and 10 respectively, and a bottom 11. The receptacle is 50 preferably mounted on casters 12 and is provided with handles 13 at convenient points. I provide a cover 14 for the receptacle, which cover is secured in position by means of screws 15 arranged therethrough and engaging with threaded brackets 16 at the corners of the receptacle. The receptacle is

receivable beneath the seat 5, suitable guides 17 and a stop 18 being arranged on the walls 2 and 3, respectively, for a purpose which will hereinafter appear. 60

The cover is provided with an opening 19 registrable with the seat opening, as shown, and an entrance member comprising a downwardly directed frusto-conical body 20 having open ends is arranged coaxially 65 of said cover and seat openings for an obvious purpose. A flange 21 is provided on the upper end of the entrance member 20 for mounting same on the cover. The lower end of the member 20 is flared as at 22 and 70 a closure 23 hinged at 24 is engaged, when in closed position, against said flared portion 22 to seal the entrance member. I provide manipulating means for the closure 23 including a bell crank lever 25 pivoted to a 75 bracket 26 and 26', one arm 27 of said lever being connected by a link 28 to the closure 23 and the other arm 29 provided with a detachable handle 30 extending through suitable slots 31 and 32 in the receptacle cover 80 and seat. In order to maintain the closure normally closed, a laterally extending arm 33 is formed on the bracket 26, and a coiled spring 34 is connected between said arm and the arm 27 of the lever 25, maintaining the 85 latter in the position shown. The arm 29 is offset as best shown in Fig. 2 to avoid interfering with a person using the closet. The closure 23 is shown open and indicated in dotted lines in Fig. 1. 90

A vent pipe 35 is provided being removably engaged, through an opening 36 in the seat, with the receptacle cover as indicated at 37, a metallic bushing 38 receiving the lower end of the pipe. The upper end of the 95 pipe may be provided with a screen 39 and a flashing 40 may be provided to limit the downward movement of said pipe.

When it is desired to remove the receptacle 8 for cleaning, the pipe 35 is raised and 100 allowed to rest on the seat. The handle 30 is now removed and the receptacle may be rolled from beneath the seat by grasping the front set of handles 13. The cover 14 may be removed by taking out screws 15 105 thereby permitting emptying of the receptacle. It will be apparent from the foregoing that I have provided an improved simple and cheap dry closet which is sanitary in every way and capable of quick and easy 110 cleansing. I do not limit myself to the use of screws for retaining the cover 14 in place,

but reserve the right to use any well known securing means suitable for the purpose.

From the above description taken in connection with the accompanying drawings, it is thought that a clear and comprehensive understanding of the construction, operation and advantages of my invention may be had, and while I have shown and described my invention as embodying a specific structure, I desire that it be understood that I may make such changes on said structure as do not depart from the spirit and scope of the invention as described.

What I claim as my invention and desire to secure by Letters Patent is:

In combination with a dry closet, a receptacle slidably arranged beneath the seat

thereof, a removable top for said receptacle having an opening formed therein, a tubular element secured to the underside of said top adjacent said opening, a closure snugly engageable with the lower end of the tubular element, a substantially bell crank shaped lever mounted on the underside of the top having one end connected to the closure and the remaining portion thereof off-set laterally and extended through said top and seat, and spring means engaged with the lower portion of said lever for normally maintaining said closure in engagement with the lower end of the tubular element.

In testimony whereof I affix my signature hereto.

CARL V. VOELKER.
